US0D1111211S

(12) **United States Design Patent** (10) **Patent No.:** **US D1,111,211 S**
(45) **Date of Patent:** **** Feb. 3, 2026**

(54) **WORKING LIGHT**

(71) Applicant: **Ningbo Vertak Mechanical & Electronic Co., Ltd.**, Ningbo (CN)

(72) Inventor: **Bin Zeng**, Ningbo (CN)

(73) Assignee: **Ningbo Vertak Mechanical & Electronic Co, Ltd.**, Ningbo (CN)

(**) Term: **15 Years**

(21) Appl. No.: **29/901,144**

(22) Filed: **Aug. 29, 2023**

(51) LOC (15) Cl. **26-05**

(52) U.S. Cl.

USPC **D26/65**; D26/102

(58) **Field of Classification Search**

CLAIM

The ornamental design for a working light, as shown and described.

DESCRIPTION

FIG. 1 is a top perspective view of a working light, showing my new design;

FIG. 2 is a bottom perspective view thereof;

FIG. 3 is a front view thereof;

FIG. 4 is a rear view thereof;

FIG. 5 is a left side view thereof;

FIG. 6 is a right side view thereof;

FIG. 7 is a top view thereof;

FIG. 8 is a bottom view thereof; and,

FIG. 9 is another perspective view thereof, shown in an alternate state of use.

The broken lines in the drawings illustrate the portions of the working light, which form no part of the claimed design.

1 Claim, 9 Drawing Sheets
